(57) CLAIM

The ornamental design for a sink caddy, as shown and described.

DESCRIPTION

FIG. 1 is a front perspective view of a sink caddy showing the design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines in the drawings are for the purpose of illustrating environmental structure and form no part of the claimed design. The sink caddy includes a tray, a holder and an insert within the holder. The tray is not claimed. The insert within the holder is not claimed.
